HAIR WAVING MACHINE

Fernan O. Conill, New York, N. Y.

Application January 23, 1937, Serial No. 122,056
In France April 27, 1936

13 Claims. (Cl. 132—36)

This invention relates to hair waving apparatus and more particularly to an apparatus in which superheated steam is employed as the hair treating medium.

5 An object of my invention is to provide a hair waving apparatus which generates its own steam.

Another object of my invention is to provide a hair waving apparatus, the operation of which may be timed by a coin-controlled mechanism.

10 Still another object of my invention is to provide a hair waving machine having a coin-controlled timing mechanism which may be interrupted before the completion of its predetermined timed cycle.

15 A still further object of my invention is to provide a hair waving apparatus which prevents danger of injury to the person being treated.

Yet another object of my invention is to devise a hair waving machine which provides automatically controlled features to prevent injury to the apparatus due to non-functioning of any of the several elements promoting its operation.

20 A still further object of my invention is to provide a hair waving apparatus which is provided with a signal for informing the operator that the waving operation is nearing its completion.

25 Yet another object of my invention is to provide a hair waving apparatus in which there is a minimum of condensation of incoming steam.

30 With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

Briefly, my invention comprises winding a lock 35 of hair on a bobbin which is positioned within a hair treating chamber. The hair is automatically wound on the bobbin by means of a drive connection. A suitable arrangement is provided whereby the tension exerted by the hair on the bobbin 40 when it is completely wound, will disconnect the bobbin from the drive connection.

The steam for treating the hair is generated in a boiler which is an integral part of the apparatus. The steam is conducted from the boiler 45 to the waving chamber by a flexible conduit. A second flexible conduit surrounds and is concentric with the first-mentioned conduit. The second conduit is used for carrying away the steam after it has circulated through the waving chamber and treated the hair. By having the out-

going conduit surrounding the incoming conduit, there can be no condensation of the steam going into the hair treating chamber.

After the steam leaves the treating chamber it is mixed with air and is withdrawn by a suction 5 fan. The condensed water is carried to a slide drawer from which it can be removed in any desired manner.

Prior to its entry into the hair waving chamber, the steam is superheated by passage over an electrical heating element. A switch interposed in the circuit will break the circuit to the heating element when the steam has attained a certain pressure. Moreover, the current, as well as the generation of steam, can be governed by a switch arrangement which is actuated by a timing mechanism.

Inasmuch as the timing mechanism is a coin-controlled device, it is necessary to deposit a coin 20 therein, which, when it drops into a reservoir, causes the timing mechanism to operate, and the current necessary for the functioning of the system is established. Near the end of the operation of the timing mechanism, the operator of 25 the machine is warned by the ringing of a buzzer, and finally a switch which is actuated by the timing mechanism breaks the electrical circuit and stops movement of the timer.

In order to make my invention more clearly understood, I have shown in the accompanying 30 drawings means for carrying the same into practical effect without limiting the improvements in their useful applications to the particular construction, which, for the purpose of explanation, have been made the subject of illustration.

In the drawings,

Figure 1 is an elevational view, partly in section, showing my invention;

Figure 2 is a diagrammatic showing of the wiring circuit;

Figure 3 is an elevational view, partly in section, showing my boiler;

Figure 4 is a sectional view of my socket member;

Figure 5 is a view taken along the line 5—5 of 45 Figure 4;

Figure 6 is a view taken along the line 6—6 of Figure 3;

Figure 7 is a top plan view of the timing mechanism;

Figure 8 is a view taken along the line 8—8 of 50 Figure 7, looking in the direction of the arrows;

Figure 9 is a view taken along the line 9—9 of Figure 7, looking in the direction of the arrows;

Figure 10 is a view taken along the line 10—10 55

of Figure 7, looking in the direction of the arrows;

Figure 11 is a longitudinal section of my waving mechanism;

Figure 12 is a horizontal sectional view of the machine shown in Figure 11.

Referring now to the drawings, and more particularly to Figure 1, there is shown a housing 1 which is suitably supported upon a base 2. The base 2 contains a slide drawer 3 and a transformer 4. The slide drawer 3 is employed as a trap for the condensed water withdrawn from the waving machine.

A horizontal support element 5 is suitably affixed to the interior of the housing 1. A valve casting 6 is attached to the base 2 by bolts, as shown at 7. A steam generator or boiler 8 of small capacity is positioned above and supported on a shaft 9. Positioned in the upper portion of the housing is a coin-controlled timing mechanism 10 which is supported by an upright bracket 11 secured to the horizontal support 5. A coin reservoir 12 is positioned below the timing mechanism 10 for receiving the coins deposited therein.

Positioned in the housing is a pilot light unit 10' comprising lamps which may be viewed through colored lens 10'' in the wall of the housing.

An electric motor 13 is also affixed to the support 5 and a suction fan 14 is attached to the top of the motor. A socket 16 is mounted in an aperture 17 adjacent the top of the housing and into the socket is fixed one end of a flexible conduit 19, the opposite end of which carries the waving machine, depicted generally at 18.

Referring more specifically to Figures 11 and 12, my waving machine 18 is shown somewhat in detail. This hair waving unit is fully described in my copending application Ser. No. 108,485 filed October 30, 1936, and therefore only a brief description will be given here.

The waving machine comprises an insulated handle 20, in one end of which is fixed the flexible conduit 19, which contains the steam inlet and outlet conduits 21 and 22, the flexible drive cable 23, and a superheater line 24. Into the opposite end of the handle is fitted a cylinder 25 comprising a steam superheating chamber 26 and a hair treating chamber 27 in which the lock of hair to be waved is contained. The chambers 26 and 27 are separated by a rotary valve 28.

The open end of the hair treating chamber 27 is sealed by a shutter 29 which is actuated by a pinion 30 and rack 31 which is moved by a cam 32 attached to an operating knob 33.

Within the handle 20 is contained the mechanism for winding a lock of hair. This mechanism is driven by the flexible cable 23 and comprises a clutch 34, one member of which is driven by the cable 23, the coacting member being splined to one end of a spindle 35. A pivoted bell crank lever 36 is interposed between springs 37 and 38 and actuated by a button 39 in the handle and functions to engage and disengage the clutch. The faces of this clutch are so arranged that when a certain tension has been exerted on the wound lock of hair, the faces will override each other to prevent further winding.

However, as is well known, in waving a lock of hair it is necessary to wind the hair tightly. In order to accomplish this, a ratchet wheel 40 is provided on the spindle 35. The ratchet wheel 40 and the spindle 35 are rotated by means of a lever 41 to which is attached a pawl 42. A back pawl 43 is provided to prevent reverse rotation

of the ratchet. The spindle 35 extends forwardly into the hair treating chamber 27 and carries on its end a tapered arbor 44. This arbor is adapted to fit into a socket 45 in one end of a bobbin 46. The bobbin 46 is removable from the chamber 27 and is held on the arbor by means of a helical key which cooperates with helical grooves in the socket 45.

The incoming steam from the boiler 8 passes from the conduit 21 through a duct 47 into the superheating chamber, where it passes over a heating coil 49. As shown diagrammatically in Figure 2, the coil 49 is grounded at one end, designated 50 in Figure 11. The opposite end is connected to the lead wire 24 from the transformer 4. After being superheated, the steam enters a hair treating chamber through an orifice 51 where it comes in contact with and heats the hair wound on the bobbin.

After the steam leaves the hair treating chamber, it again passes through the valve and enters into a duct 52 which is in communication with the return conduit 22, as shown at 53 in Figure 12.

Also fitted into the handle 20 and positioned below the cylinder is a trough-like guard member 55 which is provided with an air duct 56. The air duct 56 is in communication with the flexible conduit 22, and through this arrangement, with the suction fan 14. During the waving operation, it is this guard portion of the apparatus which is constantly in contact with the head of the person being treated. Inasmuch as air is being continuously drawn through the duct, it will of course keep the guard cool and prevent scalp burns, which are so common in the conventional type of hair waving apparatus.

An aperture 58 is provided in the trough of the guard and communicates with the air passage. This aperture provides an aspirating orifice through which any condensed steam which should fall in the trough may be removed to the slide drawer 3 in the base of the casing 2.

As pointed out, the flexible conduit 19 carries the steam inlet and outlet conduits 21 and 22, the drive 23, and the lead wire 24 to the superheater in the steam chamber. The boiler 8 for generating the steam to be supplied to the conduit 21 and the waving machine 18 is perhaps best depicted in Figure 3.

I have found that to devise an efficient boiler of small capacity, it is necessary to provide a constant water feed which is proportional to the consumption of the steam in order to assure a constant and equal flow of the steam. This can be accomplished by automatically utilizing the changes in the weight of the boiler 8.

Inasmuch as the boiler 8 is completely covered in my copending application, I shall describe the boiler briefly.

As heretofore pointed out, the boiler 8 is supported above the valve casing 6 by a shaft 9. The boiler comprises an inner and outer shell 60 and 61, respectively. Heat insulating material 62 is placed between the shells 60 and 61. A tube 63 is centrally arranged with respect to the inner and outer shells. Suitably secured to the outer shell at the top and bottom portions thereof are closure members 64 and 65.

A spacer bushing 66 is threaded onto the upper end of the tube 63 and is positioned between the top member 64 and the inner shell 60. A cap 67 is also screwed onto the end of the tube 63 and fits snugly within the spacer bushing. A flanged nut 68 is screwed onto the opposite end of the tube 63.

tube 63 within the bottom portion 65. A second nut 69 is also screwed onto the end portion of the tube on the outside of the bottom member. It will be appreciated that a steam-tight fit between the tube 63 and the inner shell 60 may be effected by brazing or some other suitable method. The shaft extends through the tube and is secured to the top portion of the valve casing, as at 70. The other extremity of the shaft extends through a cross bar 73 and is held in position by a nut 74. Threaded rods 75 extend through apertures adjacent the ends of the cross bar and nuts 76 hold the rods in proper position. One of the free ends of a spring 77 is fitted to each of the rods 75.

A pair of radial arms 78 are suitably secured to the bottom 65 of the boiler. These arms are likewise provided with threaded rods 75' which are attached to the ends of the arms and carry the opposite free ends of the springs 77. The springs 77 are adapted to normally force the boiler 8 toward the cross bar.

Also carried by the cross bar 73 at one of its ends is a bracket 79. The bracket 79 supports a lever arm 80 which is provided with a down-turned portion 81 which is adapted to contact the top 64 of the boiler. A counterweight 82 is also carried by the arm 80 and also serves as a stop member by engaging the cross bar 73. A clip 83 is supported by the bracket and carries a mercury switch 84 therein. The arm 80 and the clip 83 are adjustably mounted on the upright 79 so that they may be adjusted to suit any desired condition.

As the boiler is adapted to be vertically displaced, and in order to concentrically locate the shaft and the tube 63 and to permit free movement of the boiler, the cap 67 and the nut 69 are provided with anti-friction rollers 85.

The following valve arrangement has been devised so that the water may be fed proportionately to the consumption of the steam. A lever arm 86 is pivotally mounted in an aperture as at 87. The pivotal connection 87 carries a pair of depending arms 88. The lever arm 86 is provided with an offset portion 90 which carries an adjustable stop 91 which is adapted to be contacted by the bottom 65 of the boiler 8 when the weight of the boiler increases. The depending arms 88 are secured to a collar 92 by means of pins 93. Apertures 94 are provided in the collar. Attached to the collar at one end thereof are a pair of flexible conduits 95 and 96. The conduit 95 is secured at its free end to a disc 97 which is suitably affixed to the end wall of the casing. A fitting 98 is screwed into the disc 97. The above described structure comprises the egress portion of my feeding valve.

The conduit 96 is secured at its free end to the inner section 99 of the chamber 100. Suitable washers are interposed between the inner section 99 and the outer section 101 of the chamber 100 and they also serve to support a screen 102. Obviously, this screen will prevent any foreign matter, such as grit, which might be in the water from entering the boiler. The outer section 101 is connected to a suitable source of water by a hose connection 103. The inner section 99 is provided with an adjustable valve 104 which is centrally screwed therein. Rubber washer 105 is held in place by a nut 106 and will prevent any leakage around this valve. A sleeve 107 is fitted onto the end portion of the fitting 104 and a needle 108 extends therethrough and is adapted to open and close the valve 104. The stem 109

of the needle is adapted to contact the central portion of the collar 92. This valve structure constitutes the automatic feeding arrangement for the water.

Secured to the fitting 98 by a screw cap 110 is the end fitting 111 of a flexible conduit 112. The other end of the flexible conduit terminates in a sleeve 113 which is fitted into an elbow 114 which extends through apertures in the bottom 65 of the boiler and the lower wall of the inner shell 10. This fitting of course is provided with a central bore in order to permit the water to enter into the boiler.

A similar elbow fitting 115 having connected thereto a flexible conduit 116 is provided in the upper portion of the boiler. A safety valve 117 is also provided in the top of the boiler.

Extending through openings in the lower wall of the inner shell are a pair of cup-shaped members 118, each of which is provided with a flanged ring 119 which is soldered to the inner shell. Electrical heating elements, depicted generally at 120, are screwed up into the cups 118. The heating elements are provided with terminals 121 which extend downwardly therefrom through apertures in the bottom closure of the outer shell. Suitable insulating discs 122 are provided on the terminals to form a closure for the openings in the bottom member 65.

Contact points 124 extend through apertures 125 in the upright portion 126 of the casing for connection with a source of electrical energy, such as the plug 127 shown in Figure 1. Insulating washers 128 are fitted onto the contacts to insulate the same from the metal casing.

The flexible conduit 116 is in communication with the steam inlet conduit 21 of the waving machine 18 and communicates with the boiler 8 through a four-way connection 130 which is screwed into an aperture 131 in the upper portion of the socket 16.

The socket 16 is provided with a bore 132. A metallic plug 135, which carries the flexible tube 19, is fitted within the bore 132 of the socket. A flanged screw cap 136 which is screwed on the end of the socket holds the plug and its associated parts in proper position. The plug 135 is provided with longitudinal bores 137, 137' and 138 into which are fitted the ends of the conduits 21 and 22 and the flexible transmission cable 23 respectively. The lead wire 24 to the heating coil 49 in the steam chamber extends through an aperture 139 in the plug in which is fitted a suitable insulating bushing 140. The steam outlet conduit 22 communicates with an aperture 141 in the plug by means of a passageway 142. As shown in Figure 4, the aperture 141 communicates with an elbow 143 which is secured to the lower portion of the socket beneath the bore 132, as indicated at 144. The other end of the elbow 143 is fixed to and communicates with the interior of the suction fan 14. A conduit 14' is attached to the discharge side of the fan 14. The opposite end of the conduit 14' connects with a passage 3' which is in communication with the interior of the receptacle 3.

A tapered fitting 145 is screwed into the aperture 133 which communicates with the aperture 131 in the socket and the tapered end thereof fits into a tapered portion 146 of the bore 137' so as to permit the steam from the boiler 8 to pass into the inlet conduit 21.

The flexible transmission cable 23 is secured to a drive shaft 148 which extends through the socket by means of a splined coupling 149. The

coupling 149 is provided with an enlarged portion 150 which is held in position by an internally shouldered cap 151 which is screwed into the plug 135. The shaft 148 carries a pulley 152 at its outer extremity.

Referring now to Figure 1, it can be seen that the shaft 153 of the motor carries a small pulley 154 and a large pulley 155 at its outer end. A drive belt 156 is fitted around pulleys 154 and 10 152 for transmitting rotary motion to the drive shaft 148, which will in turn drive flexible cable 23 through the coupling 149. It will of course be readily appreciated that this movement will be transmitted to the bobbin to permit the lock 15 of hair to be wound thereon, as previously pointed out.

The drive shaft 157 of the suction fan also carries a pulley 158. The belt 159 is fitted around the large pulley 154 on the drive shaft of the 20 motor and the pulley 158 for transmitting motion to the suction fan. Thus it can be seen that as long as the motor is operated, the fan and the drive shaft 148 will be continuously driven.

As shown in Figure 1 a pressure gauge 160 is 25 fixed in an aperture in the wall of the housing 1 for indicating the pressure of the steam in the boiler 8. A flexible conduit 161 is secured at one end to the gauge and at the other end to the four-way connection 130. It will be appreciated 30 that this gauge will permit the user to be informed of the pressure in the boiler 8.

Referring now to Figure 4, it can be seen that an upright bracket 163 is secured to the socket 16 as indicated at 164. The bracket carries a contact 165 and a terminal 166. Fitting within the connection 130 is a bellows 167 which is provided with a contact point 168. The contact point 168 is adapted to make contact with the point 165 when the pressure attained in the boiler 8 is sufficient to expand the bellows so as to move point 168 into engagement with point 165. As will later become apparent, this structure will permit the feeding of electrical current to the transformer 4 and thence to the heating element 49 contained within the steam heating chamber 45 of the waving unit 18.

As has heretofore been pointed out, the operation of the system is controlled by a timing mechanism 10 which is actuated by a coin-controlled device. This timing mechanism is perhaps best depicted in Figures 7 to 10 inclusive. Broadly, the timer consists of a casing 170 in which is positioned two mercury switches 171 and 172 which are series connected in the feeding circuit. Also carried in the casing is a gear train 173 whose speed may be varied by an escapement 174. A coin-actuated device 175 operates a bar 176 to wind the spring of the gear train 173. A counting mechanism 177 is also actuated by the bar 176. A buzzer 178 is provided so as to inform the operator of the machine that the duration of the waving operation is nearing its completion.

Referring more specifically to the timing mechanism and especially Figure 8, I have shown a bracket 180 which is suitably fixed to the bottom of the casing 170. A shaft 181 is centrally positioned with respect to the bracket and is suitably journaled in the bottom of the casing. The shaft extends through an aperture in the top of the bracket and is provided with a collar 182. A lever arm 183 is keyed to the upper end of the shaft and is provided at its outer end with a finger grip 184. As best shown in Figure 10, the arm 183 extends through an elongated aperture 185 provided in the wall of the housing 1. The

aperture 185 is of such size as to limit the movement of the arm 183. Also secured to the shaft 181 immediately below the arm 183 is a ratchet wheel 186. A spring pressed pawl 187 is secured to the lower portion of the lever arm 183 which engages the teeth of the ratchet wheel.

Suitably secured to the ratchet wheel is a revoluble disk 188 which is provided with a plurality of notches 189 located in the outer periphery of the disk. A spring-pressed dog 190 is adapted to 10 engage the notches 189 for a purpose which will later become apparent. A plurality of diametrically opposed openings 191 of sufficient diameter to receive a coin are provided in the disk. The housing 1 is also provided with an aperture 192 15 to permit access to one of the openings 191.

Also carried by the shaft 181 is a segmental member 193 the configuration of which is shown in dotted lines in Figure 7. The member 193 carries a gear 194 along its outer edge. The 20 bracket 180 is provided with an aperture 195 located above the coin reservoir.

The gear 194 meshes with a gear wheel 196 of the gear train 173. Secured to the gear wheel 196 is a smaller gear 197. The gear 197 is adapted 25 to mesh with teeth 198 provided in the bar 176. As clearly shown in Figure 7, the bar 176 is supported in guides 199.

Also carried by the staff 200 on which is mounted the gear wheels 196 and 197 is a clock 30 spring 201 which is wound by rotating the staff 200 through medium of the lever arm 183. A ratchet 202 is pinned to the staff 200 and a pawl 202' is provided on the large gear 173' of the gear train 173 for the purpose of imparting motion thereto. The escapement 174 is provided with an adjustable weight 203 so that the speed of the timing mechanism may be varied by shifting the weight on its associated rod.

Mounted in brackets 204 is a shaft 205 which 40 carries at one end thereof the mercury switch 171. The other extremity of the shaft 205 carries an arm 206 which extends over the bar 176. A spring 207 is adapted to hold the switch in either the "on" or "off" position.

A plunger rod 208 extends through an aperture in the casing 170 and is provided with an operating button 209 at its outer end. The plunger is journaled in a collar 210 secured to the inside wall of the casing. The rod 208 carries an arm 211 which is adapted to move in an elongated slot provided in the clip 212 of the switch 172. A pin 213 adjacent the end of the rod 208 engages the rod of the escapement 174 to arrest movement of the gear train. Obviously, it is necessary 55 to withdraw the plunger 208 in order to begin operation of the system.

Pins 214, 215 and 216 are provided on the bar 176. A lateral projection 217 is also carried at the end of the slide 176 for tripping a bell crank 60 lever 218 mounted in a bracket 219 carried by one of the guides 199. A link 220 connects the crank arm with the counting mechanism 177 through the operating lever 221.

Let us assume a coin has been deposited in 65 the aperture 191. The coin falls through the aperture and rests on the upper wall of the bracket 180 and the edge thereof abuts the segment 193 and the periphery of one of the apertures 191. The handle 183 is then turned carrying with it the disk 175 and the segment 193 by means of the coin which will slide on the bracket until it arrives above the aperture 195. When the coin reaches this point, it will, of course, fall through the aperture into the coin reservoir. 70 75

This movement of the disk and the segment 193 through the medium of the gear 194 and gear 196 winds the spring 201 of the gear train 173. Likewise, the smaller gear 197 moves the bar 176 toward the right. In the course of its movement the pin 214 will engage the arm 206 and move the mercury switch 171 to its "on" position thereby establishing an electrical circuit. This movement of the bar will cause the lug 217 to engage the 10 crank arm 218 to operate the counting mechanism 177.

When the arm 183 is released after completing its cycle, the spring 223 on the shaft 181 will bring the arm 183 back to its initial position.

15 It will be readily appreciated that the system is now ready to function. The plunger rod 208 is then pulled out freeing the escapement 174 and permitting the operation of the gear train. The slide 176 will then start to move in an inverse direction through medium of the gear train 173. This movement continues until the pin 215 trips the arm 206 of the switch 171 whereby the electrical circuit will be broken. However, in the event it is desired to interrupt operation or to 25 stop it before the completion of the timed cycle, the plunger rod 208 is actuated to engage the pin 213 with the escapement rod. This will arrest the timing mechanism and also trip the mercury switch 172 to break the electrical circuit.

30 Connected in series with the buzzer 178 is a switch 225 adapted to be actuated by the pin 216 on the bar 176. When the bar 176 nears the completion of its movement, this pin will close the switch 225 to complete the electrical circuit to the buzzer 178 to warn the operator that the timing device is near the completion of its function. As described later, this switch 225 is also connected in series with the main operating circuit and obviously will cease its function when 40 the switch 171 is moved by the bar 176 to its "off" position.

It will be readily appreciated from the foregoing that I have devised a hair waving machine which is provided with automatically controlled features to prevent injury to the machine due to the non-functioning of any of the elements effecting its operation. Moreover, the apparatus prevents any danger of injury to the hair or scalp of the person being treated.

45 The function of the electrical units of the apparatus is perhaps best understood by reference to the wiring circuit shown in Figure 2.

When the contact points 124, 124' are connected with a source of electrical energy, current 55 flows from point 124 through a common lead 300 to the primary coil of the transformer 4; the mid point of the heating element 120; one terminal of the motor 13 and to the common lead of the pilot lamps 10'.

60 Current from point 124' flows through lead 301 through switches 171, 172 and 84 which are serially connected and thence to the point 302. From point 302, the current flows through a line 304 to the heaters 120 completing the circuit 65 thereto. The current also passes from point 302 through a lead 305 to the other terminal of the motor and through a lead 304' to the pilot light 10'.

Let us assume that a coin has been deposited 70 in the coin control 175 and the timing mechanism has been set in operation. This will of course complete a circuit to the main switch 171 and by manually operating the plunger 208 the switch 172 is also closed. As soon as sufficient 75 water has been fed into the boiler, the switch 84

will close and current will be supplied to the heating elements 120. At this time the circuit is completed to the white pilot lamp 10'. The heating elements 120 will generate steam in the boiler which will collect in the upper portion 5 thereof and will leave through conduit 116. When sufficient steam pressure is attained, it will expand the bellows 167 making contact between points 165 and 168 and complete the circuit to the red pilot light 10' and to the primary of 10 the transformer 4. Current will be induced to the secondary of the transformer and will complete the circuit to the coil 49 in the hand waver 18. The secondary is grounded at 309 and the coil 49 is grounded at 50. The transformer will 15 feed current to the heating element 49 in the chamber 26 for superheating the steam before its passage into the hair treating chamber 27.

In order to minimize the danger of electric shock from the waving machine 18, a low volt- 20 age is supplied to the heating element 49.

As soon as the steam pressure is diminished the bellows will contract and break the circuit to the red pilot light 10' and to the heating element 49 in the waving machine. It is apparent, therefore, that when the red lamp 10' is off, no current is being fed to the heater 49. As soon as the predetermined cycle of the timing mechanism is completed, switch 171 will break the circuit and as the switches 171, 172 and 84 30 are serially connected, the operation of the apparatus will be arrested. If for any reason it is desired to cease operation before the cycle is completed, manual actuation of switch 172 will likewise break the circuit and stop the functioning of the machine. 35

If from accidental stoppage of the water line or from any other reason that might cause the water in the boiler to fall to a critical level which might cause damage, the switch 84 will be actuated to open the circuit to the heating elements 120. 40

The switch 225 which is connected in series with the buzzer 178 and with the low voltage line from the transformer 4 is adapted to complete the circuit to the buzzer when the timing mechanism has reached the completion of its 45 cycle.

It is contemplated that I can change the mechanism for coin control to one which will register 50 the time of operation of the machine, so that a charge can be made for the use of the machine on a time basis.

While I have shown and described the preferred embodiment of my invention, I wish it to 55 be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In an apparatus for waving hair, a waving mechanism, an electrically operated device for generating steam, a conduit associated with said device for conveying steam to the waving mechanism, a second conduit concentric with said first conduit for conveying the steam from the waving mechanism after the waving operation. 65

2. In an apparatus for waving hair, a waving mechanism, a boiler for generating steam, a conduit associated with said boiler and said hair waving mechanism to convey steam to the hair waving mechanism, and a second conduit concentric 70 75

with the first conduit for conveying the steam from the waving mechanism after the waving operation.

3. In an apparatus for waving hair, a waving mechanism, an electrically operated boiler for generating steam, a conduit associated with said boiler and said hair waving mechanism to convey steam to the hair waving mechanism, and a second conduit concentric with and surrounding the first conduit for conveying the steam from the waving mechanism after the waving operation.

4. In an apparatus for waving hair, a waving mechanism, an electrically operated boiler for generating steam, a flexible conduit connected with said boiler and the waving mechanism for conveying steam from the boiler to the waving mechanism, a second flexible conduit concentric with and surrounding the first conduit for conveying the steam from the waving mechanism after the waving operation, and means associated with said second conduit for withdrawing the steam.

5. In an apparatus for waving hair, a waving mechanism, an electrically operated boiler for generating steam, a flexible conduit connected with said boiler and the waving mechanism for conveying steam from the boiler to the waving mechanism, a second flexible conduit concentric with and surrounding the first conduit for conveying the steam from the waving mechanism after the waving operation, and a suction fan associated with said second conduit for withdrawing the steam.

35 6. In an apparatus for waving hair, a waving mechanism, a winding mechanism for winding a lock of hair contained within the waving mechanism, a boiler for generating steam, a flexible conduit associated with said boiler and waving mechanism for conveying steam to the waving mechanism, a second flexible conduit concentric with and surrounding the first conduit for conveying the steam from the waving mechanism after the waving operation, a suction fan associated with said second conduit for withdrawing the steam, and a motor for operating said hair winding mechanism of said suction fan.

7. In an apparatus for waving hair, a waving mechanism, a hollow guard member positioned beneath the waving mechanism and having its outer end exposed to the atmosphere, an electrically operated boiler for generating steam, a conduit associated with said boiler and waving mechanism for conveying steam to the waving mechanism, a second conduit concentric with and surrounding said first conduit for conveying the steam from the waving mechanism after the waving operation, and suction means associated with said second conduit for withdrawing steam, said suction means also aspirating air through the guard member to cool the scalp.

60 8. In an apparatus for waving hair, a hair wav-

ing mechanism, a hollow guard member positioned beneath the waving mechanism and having an open end in communication with the atmosphere, a device for generating steam, means to convey the steam to the waving mechanism, means to withdraw the steam after the waving of the hair and means to aspirate air through the hollow guard member to cool the scalp.

9. In an apparatus for waving hair, a hair waving mechanism, a hollow guard member positioned beneath the waving mechanism and having an open end in communication with the atmosphere, a boiler for generating steam, a conduit connecting the boiler with the waving mechanism to convey steam to the waving mechanism, a second conduit concentric with and surrounding the first conduit to convey the steam from the waving mechanism after the waving operation and means to aspirate air through the hollow guard member to cool the scalp.

10 10. In an apparatus for waving hair, a hair waving mechanism, a hollow guard member positioned beneath the waving mechanism and having an open end in communication with the atmosphere, a boiler for generating steam, a conduit connecting the boiler with the waving mechanism to convey steam to the waving mechanism, a second conduit concentric with and surrounding the first conduit to convey the steam from the waving mechanism after the waving operation and means to aspirate air through the hollow guard member to cool the scalp.

15 11. In an apparatus for waving hair, a waving mechanism, an electrically operated boiler for generating steam, a conduit associated with said boiler and said hair waving mechanism to convey steam to the hair waving mechanism, a second conduit concentric with and surrounding the first conduit for conveying the steam from the waving mechanism after the waving operation and suction means to withdraw the steam.

20 12. In an apparatus for waving hair embodying a hair treating chamber, a hair curling member disposed within said chamber, a source of steam, means to convey the steam to the treating chamber, an electric heater adjacent said chamber, a circuit for said electric heater, said circuit being normally closed when the apparatus is in operation, and means responsive to insufficiency of steam to control automatically said circuit.

25 13. In an apparatus for waving hair embodying a hair treating chamber, a hair curling member disposed within said chamber, an electrically operated boiler to generate steam, means to convey said steam to the treating chamber, an electric heater adjacent the chamber, a circuit for the electric heater, said circuit being normally closed when the apparatus is in operation, and means responsive to insufficiency of steam within the boiler to control automatically said circuit.

FERNAN O. CONILL.
